WATER SOFTENER

Edward W. Welp, Chicago, Ill., assignor to Graver
Tank & Mfg. Corporation, East Chicago, Ind., a
corporation of Illinois

Application April 4, 1932, Serial No. 602,940

7 Claims. (Cl. 210—30)

This invention relates to flow-limiting devices, and has been illustrated as embodied in water-softening apparatus. It has been common practice in water-softening to feed acid to a mixing sump at a rate in proportion to the flow of untreated water to that sump. In the past it has been possible under certain irregular conditions for the acid to be fed much faster than was desired. This would of course result in an excess of acid in the treated water, which would obviously be very undesirable. According to the present invention, the acid is fed from the acid tank to a surge tank which is provided with an orifice of given size communicating with the mixing sump which will accommodate the ordinary flows of acid into the surge tank, and a float operated valve which will shut off the orifice when the acid level in the surge tank is raised above a predetermined point. The orifice is preferably of such size that during a given period it will drain from the surge tank the maximum quantity of acid that can properly be supplied thereto in the same period, so that any flow of acid greater than this normal maximum will close the outlet from the surge tank. However, the level at which closure takes place is preferably enough higher than the minimum level in the surge tank so that a mere momentary excess will have no effect. Means are also provided to drain the surge tank when the abnormal conditions have been corrected, so that the apparatus can be restored to its normal operating condition.

With these and various other objects in view, the invention may consist of certain novel features of construction and operation, as will be more fully described and particularly pointed out in the specification, drawing and claims appended hereto.

The drawing is a somewhat diagrammatic sectional view of the apparatus embodying this invention, many associated parts being omitted for the sake of simplicity.

Although my invention may take many forms, only one has been chosen for illustration. Many of the features shown in the drawing are common in chemical water softener plants. The mixing sump 10 is commonly provided for mixing untreated water with the chemical. The raw water may be supplied through the pipe 12, under the float control shown diagrammatically, or any other type of control desired. The pipe 14 may be provided for supplying acid to the mixing sump.

The feed of the acid is commonly controlled by a swing pipe 16 or other metering device operated in connection with an acid feed tank 18. When

the swing pipe is used its upper or inlet end is ordinarily lowered during operation by a cable 20 unwound from a drum 22. The drum 22 may be controlled in a variety of ways, but it is preferably controlled by the flow of water in pipe 12 to unwind an amount in definite proportion to the amount of raw water flowing into the sump. One of the preferred forms of control is to insert a meter in the pipe 12 and to arrange contacts to be closed by this meter every time a given volume of water passes through the meter, and to provide a solenoid and suitable gearing for turning the drum 22 a definite adjustable amount for each closure of the contacts. This control of the drum 22 by the flow of water into the pipe 12 is not shown, inasmuch as it is already well known in various forms, and it is not necessary to the illustration of the more important features of this invention.

Ordinarily the swing pipe 16 is connected directly to a pipe such as 14 which carries the acid to the mixing sump without further control. Under such an arrangement, it is clear that if the cable 20 should break, the swing pipe would drop to the bottom of the tank, with the result that the entire contents of the acid feed tank would flow into the mixing sump. This, of course, would leave an excess of acid in the water that was drawn from the sump. The present invention overcomes this difficulty as well as similar difficulties due to other causes.

The pipe 16 is connected to a pipe 24 in which there may be provided a valve 26. This pipe 24 communicates with the surge tank 28 which in turn communicates with the pipe 14. Located in this pipe 14 is a restrictive orifice member 30, the orifice of which is ordinarily of a size which will drain acid from the surge tank 28 as fast as it will be fed thereto (except for momentary surges) by the maximum flow through the raw water inlet pipe 12. However, when the conditions of use are such that water never flows from the pipe 12 at a maximum capacity for more than an occasional brief period, the orifice 32 may be made smaller than would be necessary if there were a continual capacity flow from pipe 12 for the purpose of detecting a less extreme excess feeding of the acid.

When acid flows through pipe 24 into the surge tank at a greater rate than it can flow therefrom through the orifice 32 it will of course raise the level of acid in the surge tank 28. In order to stop the flow of acid in the mixing sump 10 if this excess feed of the acid to the surge 28 continues too long, a float operated valve is provided. In

the diagrammatic representation in the drawing, there is shown the valve 34 which is operated by lever 36, which latter is pivoted at 38 to a support 40. On the far side of the pivot from the valve is located a float 42 and there may be also provided a stop 44 for limiting the opening movement of the float 42. The float and valve are preferably arranged so that the valve will be closed only after the level of acid in the surge tank 28 has been raised to a point several inches above its normal level. The reason for this is that through the intermittent movement of the swing pipe 16, and due to surface tension of the acid, as well as due to other normal causes, flow through the swing pipe 16 will be irregular even during its proper operation. Occasionally a small quantity of the acid will flow into the surge tank at a faster rate than it can flow from said tank through the orifice 32. The location of the float in the closing position is preferably just high enough not to be affected by the greatest of these normal momentary surges and for some purposes even greater leeway will be provided to prevent the valve from being shut by any but the more extreme irregularities.

When there has been a continued excess flow to the surge tank 1, the float 42 will be raised, closing the valve 34 and preventing egress of the acid from the surge tank 28. Since there is then no way for the acid level in the surge tank to be lowered, the apparatus will be held in this position with the valve 34 closed until correction has been made. In the meantime, the water drawn from the mixing sump will be free from acid.

When the cause of the trouble has been corrected, the apparatus again may be put in operation by opening the valve 48 which will permit drainage of the acid from the surge tank 28. When the acid is drained to its normal level, the float 42 will drop, opening the valve 34 so the acid may then flow to the mixing sump in a normal manner.

The invention may be clarified by a brief description of its operation. During ordinary operation of the water softener the float 42 is in its lower position, holding the valve 34 open so that the acid is fed to the mixing sump at the same rate as if this invention were not used, except that its flow is made more uniform by the orifice 32. However, under such abnormal conditions as would cause a continued excess of flow of the acid into the surge tank, the level of the acid in the surge tank is raised to the point where the float 42 is raised and the valve 34 closed. This shuts off all flow from the surge tank 28 to the mixing sump 10, until the surge tank has been separately drained, as by means of the drain valve 48.

If it were desired to control the valve 34 more sensitively than it can be controlled when allowance is made for the greater momentary surges, this could be done by controlling the drain valve 48 or other suitable drain valve automatically in conjunction with the valve 34. Under such circumstances, the drain valve would be arranged to open upon a very slight surge of the acid in the surge tank 28, or it may be arranged to open whenever the valve 34 should close. Under the latter condition it would preferably remain open until the level of the acid in the surge tank was low enough to cause the valve 34 to open. This automatic drain valve could also be provided with a restrictive orifice, so that if the supply of acid to the surge tank was extremely excessive, the level would continue to rise until

the float closed the valve 34, at which time or subsequently thereto, the float could reclose the automatic drain valve. The operation then would be merely that if there were an unusually large but normal surge the restricted drain would release some of the excess acid and prevent operation of the valve 34, but if the cable 20 broke, so that there would be no advantage in preventing operation of the valve 34, then the drain would be insufficient and both it and valve 34 would be closed.

It is to be understood that many other embodiments of the invention, including some in improved form, will be apparent, and in the course of time more will be devised by those skilled in the art. It is not desired that this invention be limited to the details described, for its scope includes all such forms or improvements as come within the spirit of the following claims, construed as broadly as the prior art will permit.

What is claimed is:

1. Water softening apparatus including a mixing sump and a surge tank connected to empty into said sump, means to feed an apportioned quantity of a chemical into said surge tank, means to limit the rate of flow of chemical from said surge tank to said sump, and means controlled by the quantity of chemical in said surge tank for shutting off the flow to said sump when the quantity in said surge tank exceeds a given amount.

2. Water softening apparatus including a mixing sump and a surge tank connected to empty into said sump, means to feed an apportioned quantity of a chemical into said surge tank, means to limit the rate of flow of chemical from said surge tank to said sump, and means normally having no effect but effective upon a rise of level of the chemical above a predetermined level in said surge tank for further controlling the flow of chemical from said surge tank.

3. A flow-limiting device comprising a surge tank having a relatively large capacity inlet, an outlet of smaller capacity, and means to close said outlet if the level of liquid in said surge tank rises above a given point.

4. A flow-limiting device comprising a surge tank having a relatively large capacity inlet, an outlet of smaller capacity, and means to further control the flow through said outlet if the level of liquid in said surge tank rises above a given point.

5. Water softening apparatus including a mixing sump and a surge tank connected to empty into said mixing sump, means to feed an apportioned quantity of a chemical into said surge tank, means to limit the rate of flow of chemical from said surge tank to said sump, and means normally having no effect but effective upon a rise of level of the chemical above a predetermined level in said surge tank for reducing the flow of chemical from said surge tank.

6. Water softening apparatus including a mixing container, a surge tank connected to empty into said mixing container, a chemical tank, means for feeding liquid from said chemical tank to said surge tank including a pipe having an open intake which is lowered in said chemical tank in accordance with the flow of water to be softened but which by accident may be permitted to drop a substantial distance below the chemical in said chemical tank, and means in said surge tank which is normally ineffective for controlling the flow of chemical from said surge tank to said mixing container but which reduces said flow if

the flow from said chemical tank to said surge tank exceeds a predetermined value.

7. Water softening apparatus including a chemical feeding tank of the swing pipe type, in which the swing pipe is normally lowered gradually but may by accident be lowered suddenly, a surge tank connected to receive chemical from said chemical tank under the control of said swing pipe, an outlet from said surge tank to a

container for the water to be softened, the capacity of said outlet being materially smaller than the capacity of the connection between the chemical tank and the surge tank whereby the level of chemical in the surge tank will rapidly rise if the swing pipe is dropped suddenly, and means responsive to such a rise in the level of the chemical in said surge tank for closing said outlet.
